CLAIM

The ornamental design for a combined toy loader and figure therefor, as shown and described.

DESCRIPTION

FIG. 1 is a front elevational view of a combined toy loader and figure therefor, showing my new design;
FIG. 2 is a right side elevational view thereof;
FIG. 3 is a left side elevational view thereof with the
scoop member in an elevated position;
FIG. 4 is a left side elevational view thereof with the
scoop member in an alternate position;
FIG. 5 is a top plan view thereof; and
FIG. 6 is a rear elevational view thereof.

FIG. 1
